UNITED STATES PATENT OFFICE.

SAMUEL SCHUSSEL, OF NEW YORK, N. Y.

AUTOMOBILE DIRECTION SIGNAL.

Application filed April 12, 1926. Serial No. 101,462.

This invention relates to a direction signal for automobiles.

An object of the invention is to provide a simple and efficient unit which can be readily attached to an automobile and removed therefrom.

A further object is to provide a device which when attached will be firmly held in place.

10 A further object is to provide a device which is simple, efficient, durable and of economical construction.

The invention is illustrated in the drawings, of which—

15 Figure 1 is a perspective view of the device;

Figure 2 is a vertical section through the device;

20 Figure 3 is a section taken on the line 3—3 of Figure 1.

The form of the invention shown in the drawings is a preferred form, although it is understood that modifications in the construction and arrangement of the parts and 25 in the character of the materials used may be adopted without departing from the spirit of the invention as set forth in the appended claims.

In general, the idea comprises a pair of 30 casings to be disposed on opposite sides of supporting surfaces and connected by a tubular element which is preferably U-shaped the adjacent faces of the casings having suction means thereon to hold them firmly 35 against the supporting surface, which may be the window of an automobile, over the top of which window the tubular element is disposed. In one casing is a drum rotatable on a shaft to which a signal arm 40 is connected. A cable or other connection is wrapped around the drum and passes through the tubular element and at the other end is connected to an operating shaft which on the outside of its respective casing 45 has a handle. This handle has a projecting teat adapted to lie in any one of the indentations on the side of the adjacent casing so as to latch the handle in any desired position. By reason of the U shape of the 50 connecting element the whole device can be hung on the top of a window, although the connecting element can be arranged to pass through a solid wall if desired.

In the preferred form of the invention 55 however it is to be hung over the top of a

supporting surface such as a window and it can be readily put in place and removed therefrom if desired. The window can be practically closed because of the thinness of the connecting element. This enables the 60 signal to be simply, efficiently and accurately operated from the window of a car, whether the window is up or down and this clearly indicates a stop or a turn in either direction, in accordance with the usual convention. 65

In the preferred form of the invention shown in the drawings, I provide two casings, 10 and 11, which are to be disposed on the outside and inside of a supporting 70 surface respectively, which may be a window 12 of an automobile. The casings are connected by a U-shaped connecting element 13, which by reason of its shape permits the two casings to be supported 75 from the top of the window if desired, although it is possible to permanently associate the tubular element if desired through a solid wall of the car.

Within the casing 10 there is disposed a 80 drum 14 mounted on a shaft 15, carrying on its outer end a signal arm 16. Within the casing 11 is disposed a shaft 17 carrying a short arm 18 connected to one end of a cable or strap 19, the other end of 85 which is fastened to and passes around the drum 14, this strap passing up through the tubular U-shaped connecting element. On the outside of shaft 17 is an operating arm 20, the movement of which in one direction 90 is limited by a stop pin 21. This arm has a projecting teat 22 adapted to lie in any one of the series of indentations 23 formed in the face of the casing 11 adjacent the arm 20, so that the arm as it is moved will be 95 temporarily latched in any one of a plurality of desired positions. On adjacent faces of the drums 10 and 11 are disposed suction devices 24 and 25 which enable them to be firmly clamped or held against 100 the opposite sides of the supporting surface or window 12.

It will be observed, therefore, that this device can, when desired be readily slipped over the top of a supporting surface such 105 as a window to permit the signal to be easily operated from within the car whether the window is up or down.

What I claim is:—

1. An automobile direction signalling de- 110

- vice which comprises a pair of casings adapted to be disposed respectively on the inside and outside of a car, a signalling instrument supported on one casing and an operating element supported on the other casing and a tubular connection between the casing adapted to act as a means for supporting the two casings from the car and a connecting element extending through the tubular element from the operating element to the signal element, and suction means disposed on adjacent faces of the casing to adapt them to be held firmly against the supporting surface.
2. An automobile direction signalling device which comprises a pair of casings to be disposed respectively on the opposite sides of a supporting surface, a tubular connecting element extending from one casing to the other, an operating device mounted on one casing and an operated signal mounted on the other casing, a connecting element extending through the tubular element from one casing to the other, said tubular element being U-shaped to adapt the device to be slipped on the top of a supporting surface such as a window, when desired.
3. An automobile direction signalling device which comprises a pair of casings to be disposed respectively on the opposite sides of a supporting surface, a tubular connecting element extending from one casing to the other, an operating device mounted on one casing and an operated signal mounted on the other casing, a connecting element extending through the tubular element from one casing to the other, said tubular element being U-shaped to adapt the device to be slipped on the top of a supporting surface such as a window, when desired, and suction means on the adjacent facings of the

two casings to adapt them to be held firmly against the supporting surface.

4. An automobile direction signalling device which comprises a pair of casings to be disposed on opposite sides of supporting surfaces, suction means on adjacent faces of each casing, a drum within one casing, an operating shaft within the other casing, a connecting element extending from the operating shaft to the drum, a signal connected to the drum, an operating handle connected to the shaft, a tubular U-shaped connecting element extending from one casing to the other and through which said connecting cable passes, the U shape of the tubular element permitting the support of the device over the top of the supporting surface when desired.

5. An automobile direction signalling device which comprises a pair of casings to be disposed on opposite sides of supporting surfaces, suction means on adjacent faces of each casing, a drum within one casing, an operating shaft within the other casing, a connecting element extending from the operating shaft to the drum, a signal connected to the drum, an operating handle connected to the shaft, a tubular U-shaped connecting element extending from one casing to the other and through which said connecting cable passes, the U shape of the tubular element permitting the support of the device over the top of the supporting surface when desired, the side of the casing on which the operating handle is mounted being provided with a plurality of spaced indentations, said handle having a projection thereon adapted to extend into said indentations as the handle is moved to temporarily latch the handle in any desired position.

SAMUEL SCHUSSEL.
